UNITED STATES PATENT OFFICE.

JOHN C. McKEOWN, OF CHICAGO, ILLINOIS.

LATTICE-TRUSS.

1,372,078.

Specification of Letters Patent. Patented Mar. 22, 1921.

Application filed September 18, 1919. Serial No. 324,562.

To all whom it may concern:

Be it known that I, JOHN C. McKEOWN, a citizen of the United States, and resident of Chicago, in the county of Cook and State 5 of Illinois, have invented a new and useful Lattice-Truss, of which the following is a specification.

This invention relates to trusses and relates particularly to timber trusses of the 10 familiar type known as lattice trusses, comprising a bowed top chord, a bottom chord, and lattice members which connect said top and bottom chords.

Lattice trusses of the type specified are 15 often made of considerable length, trusses 100 feet and even more in length being not uncommon.

The great length of said trusses is often-times objectionable, owing principally to 20 the difficulty of transporting them from the place of manufacture to the point where they are to be erected for use.

The object of the present invention is to overcome this objectionable feature, and in 25 accordance with my present invention, I accomplish this end by making said trusses in sections of convenient length for shipping, and in providing means for rigidly connecting said sections.

30 In the accompanying drawings, in which my invention is fully illustrated,

Figure 1 is a side view of a truss embodying my present invention.

Fig. 2 is a side view on an enlarged scale, 35 of a portion of said truss at a joint connecting adjacent sections thereof; and

Fig. 3 is an enlarged view of a connected end of one of the sections thereof.

Referring now to the drawings, 1 designates the bowed top chord of the truss, 2 40 the bottom chord thereof, and 3 the lattice members which connect said top and bottom chords, comprising lattice members inclined at opposite angles to said top and bottom 45 chords.

As regards its usual features and excepting as hereinafter particularly described, 50 said truss may be of any usual or approved construction and will be readily understood by persons familiar with the art from an inspection of the drawings, without a description thereof in detail. A desirable form of truss is that which forms the subject-matter of U. S. Letters Patent heretofore issued 55 to me, No. 851,304, dated April 23, 1907,

to which reference is made for a full description thereof.

In accordance with my present invention, the truss comprises a plurality of separate sections—as shown, three sections—designated, respectively, A, A' and A² and a—a and a'—a' designating the lines of separation between adjacent sections.

At each side of the lines of separation a—a and a'—a', the connected ends of the 65 sections of said truss are reinforced and strengthened by means of struts or stanchions 4, each of which may consist of a single piece of timber or which may be built up from two or more pieces of timber, and 70 which are inserted between the top and bottom chord members, so that the adjacent faces of said struts will be in contact with each other and will coincide substantially with the lines a—a and a'—a' which define 75 the lines of separation between the ends of the sections of said truss, and which are rigidly connected by means of spikes or the like to the lattice members which cross said struts or stanchions, respectively.

The sections A, A' and A² of the truss are connected by steel spliced plates 5, which overlap the adjacent ends of the top and bottom chord members and which comprise spliced plates, secured to opposite 85 sides of said chord members. As shown, said spliced plates are secured to said chord members by means of bolts which extend transversely through said plates and chord members.

In practice, a truss is first finished complete as a unitary structure, the struts or stanchions 4 are then secured thereto at opposite sides of the proposed lines of separation or severance a—a and a'—a', the 95 number of sections depending upon the length of the truss and the length of the sections into which it is to be divided. In this form, the sections are then shipped to the place of use and the sections thereof connected by means of the spliced plates 5, the truss being then finished and ready for use.

I claim:

1. A timber truss of the type described, comprising top and bottom chords and lattice members which connect said chords, said truss consisting of a plurality of sections secured together end to end, each of said sections comprising stanchions inserted between the top and bottom chord members 110

thereof at their abutting ends, to which the lattice members intersected by the lines of severance of said sections are secured, substantially as described.

- 5 2. A timber truss of the type described, comprising top and bottom chords and lattice members which connect said chords, said truss consisting of a plurality of sections secured together end to end, each of said 10 sections comprising stanchions inserted between the top and bottom chord members at their abutting ends, to which the lattice members intersected by the lines of severance of said sections are secured, and means 15 for connecting said truss sections comprising metal plates which overlap the connected ends of the lower chord members of said truss sections, and are rigidly secured thereto, substantially as described.
- 20 3. A timber truss of the general type described, comprising a bowed top chord, a bottom chord, and lattice members which connect said top and bottom chords, said truss consisting of a plurality of sections 25 connected together end to end, stanchions inserted between the top and bottom chord members of each section at the connected ends of said sections, to which the ends of the lattice members intersected by the lines 30 of severance of said sections are secured, substantially as described.
- 30 4. A timber truss of the general type described, comprising a bowed top chord, a

bottom chord, and lattice members which connect said top and bottom chords, said 35 truss consisting of a plurality of sections connected together end to end, stanchions inserted between the top and bottom chord members of each section at the connected ends of said sections, to which the ends of 40 the lattice members intersected by the lines of severance of said sections are secured, and means for connecting the abutting ends of the chord members of different sections of said truss, substantially as described. 45

5. A timber truss of the general type described, comprising a bowed top chord, a bottom chord, and lattice members which connect said top and bottom chords, said truss consisting of a plurality of sections 50 connected together end to end, stanchions inserted between the top and bottom chord members of each section at the connected ends of said sections, to which the ends of 55 the lattice members, intersected by the lines of severance of said sections are secured, and means for connecting the abutting ends of the chord members of different sections of said truss consisting of metal plates which overlap the abutting ends of the sections of the lower chord and are rigidly secured thereto, substantially as described. 60

In testimony that I claim the foregoing as my invention, I affix my signature this 5th day of September, 1919.

JOHN C. McKEOWN.
